UNITED STATES PATENT OFFICE.

WILLIAM W. WOODS, OF SPRINGFIELD, MISSOURI, ASSIGNOR TO WOODS-EVERTZ STOVE CO., OF SPRINGFIELD, MISSOURI.

DESIGN FOR A STOVE.

42,345.

Specification for Design. Patented Mar. 19, 1912.

Application filed December 19, 1911. Serial No. 666,848. Term of patent 3½ years.

To all whom it may concern:

Be it known that I, WILLIAM W. Woods, a citizen of the United States, residing at Springfield, in the county of Greene and State of Missouri, have invented a new, original, and ornamental Design for Stoves, of which the following is a specification.

Reference is had to the accompanying drawing, in which the figure is a perspective view of a stove, showing my ornamental design.

I claim:

The ornamental design for a stove, as shown.

In testimony, that I claim the foregoing as my own, I have hereto affixed my signature in the presence of two witnesses.

WILLIAM W. WOODS.

Witnesses:
